LEON B. YEISER AND ARTHUR I. FISCHER, OF CLEVELAND, OHIO, ASSIGNORS TO THE FIRM OF GLAUBER BRASS MANUFACTURING COMPANY, OF CLEVELAND, OHIO, CONSISTING OF MORRIS GLAUBER AND THE ESTATE OF J. H. GLAUBER.

WALL-FITTING.

1,314,584.

Specification of Letters Patent. Patented Sept. 2, 1919.

Application filed September 19, 1916. Serial No. 120,987.

To all whom it may concern:

Be it known that LEON B. YEISER and ARTHUR I. FISCHER, citizens of the United States, residing at Cleveland, in the county 5 of Cuyahoga and State of Ohio, have invented new and useful Improvements in Wall-Fittings, of which the following is a specification.

This invention pertains to a fitting designed more especially as a wall connection for a combination hot and cold water cock or faucet for recess or corner bath-tubs, but the fitting is also more or less generally adaptable for use in or with kitchen and 15 slop sinks, laundry trays, wall showers, shampoo cocks and the like, all substantially as shown and described herein and more particularly pointed out in the claims.

In the accompanying drawings Figure 1 20 is a front elevation of what may be regarded as a bath-tub installation, and Fig. 2 is a plan view thereof. Fig. 3 is a side elevation of either Fig. 1 or Fig. 2, and Fig. 4 is a sectional elevation of one of the fitting members complete, two such members 25 being required to complete the installation.

Modern architecture for hotels and public houses especially, and in some instances in private dwellings, has come to look with 30 favor on the plan of concealing the water supply pipes in the walls of the building and providing for connections to be made directly therewith through the wall, but it has been found that in cases wherein hot 35 and cold water pipes are run parallel the pipes are liable to be spaced apart at different widths from floor to floor and in different buildings, and hence a fitting or fixture which comes to such conditions must 40 be adapted to accommodate itself to such different widths or it cannot be used. A like trouble arises in cases where the nipples for making connections may come at different elevations horizontally. Hence the 45 necessity of having fittings that can be set into any and all such varying conditions as they may arise, and have the means of adaptation in themselves by adjustment or otherwise.

50 To these ends the present invention comprises a fitting *a* which meets the needs of the conditions described and which otherwise is adapted to be used with the usual water cock *c* and which may be of the pres-

ent or any other suitable design or style 55 and provided with hand controlled valves as usual. The said fittings are preferably shaped as shown but modifications thereof may be made and come within the present invention, as is obvious. However, the present form or shape has special advantages in 60 that the fitting is made in a single piece and yet can be adapted to any irregularities in positions of the pipes that are likely to arise and without special adjustments of parts 65 or other requirements to make the necessary connections with said pipes or the so-called cock or body *c*. In addition to this the said fitting is provided with means by which the water can easily be shut off by an unskilled 70 person when such action becomes necessary. Each fitting, therefore, has a body portion 75 provided with an internal thread at its inner end, in this instance, adapted to be coupled with the supply pipe *d* by means of a nipple 3 or the equivalent thereof, and a right angled tubular elbow or arm 4 is cast integral with the body and coupled with the cock *c* by a nut 5 as seen in Fig. 4. The said nut engages a screw collar *s* on the extremity of the elbow so that a rotatable union may be effected with the cock, and a like rotation of the fitting axially may also occur at nipple 3 which connects by a screw joint with the supply pipe *d*. 80

It will also be seen that the body 2 has an extension in front of elbow 4, and that a diaphragm 6 is provided in body 2 next within the shoulder or entrance to said elbow which provides a seat for a shut-off 90 valve *v*. The said valve is preferably of the compression type and provided with a stem 7 which projects out to the front of said body where it is fashioned to apply a wrench or tool to turn the same, but which end ordinarily is covered by a cap 8 screwed onto the end of the packing nut *n* engaged on the end of said body. In this instance also a thimble 9 is inserted in the end of said body in which the said stem has screw threaded adjustment, and thus any one who has a key can easily shut off the water and detach the cock *c*. This location of the said elbow on the body of the fitting brings the same out away from the wall *w* into convenient position for use with a bath tub or sink, but it will be observed that the connection is wholly independent of the tub 100 105

or sink and supported exclusively from the wall. A screw flange 10 engaged with external screw threads on body 2 serves to clamp the fitting in place upon the wall.

5 Each fitting *a* is thus shown to be rotatable and in the rotation the arms 4 will occupy different positions in respect to a horizontal plane according to the distance or space between the supply pipes in the 10 wall and the respective elevations of the connections with the said pipes, and no adjustment of any kind is required for the various positions the fitting may take except the rotation of the fitting bodily and 15 as a whole.

What I claim is:

1. As a new article of manufacture, a hot and cold water cock or faucet and two fittings rotatably connected therewith and 20 each comprising a tubular body internally threaded at its inner end to establish a rotatable connection with a supply pipe and externally threaded to receive a screw-flange for clamping the fitting adjustably back 25 and forth upon a wall and provided internally with a valve seat and an extension front of said seat, a valve adapted to said seat having an operating stem extending through the said front extension and packed 30 therein and a screw cap for said front end inclosing the end of the said stem, and each of said bodies having a tubular elbow open-

ing into the same immediately in front of said valve seat and the outer terminals of said elbows parallel to said body and having 35 a rotatable connection with said cock or faucet.

2. As a new article of manufacture, a hot and cold water cock or faucet and two fittings rotatably connected therewith and 40 each comprising a tubular body internally threaded at its inner end to establish a rotatable connection with a supply pipe and externally threaded to receive a screw-flange for clamping the fitting adjustably 45 back and forth upon a wall and provided internally with a valve seat and an extension front of said seat, a valve adapted to said seat having an operating stem extending through the said front extension and packed 50 therein and each of said bodies having a tubular elbow opening into the same immediately in front of said valve seat and the outer terminals of said elbows parallel to said body and having rotatable connection with said cock or faucet. 55

In testimony whereof we affix our signatures in presence of witnesses.
